CAN PUNCH AND VENT

Filed Nov. 15, 1926

ATTORNEYS.

UNITED STATES PATENT OFFICE.

CHARLES W. BASSETT AND EDNA M. BASSETT, OF ALAMEDA, CALIFORNIA.

CAN PUNCH AND VENT.

Application filed November 15, 1926. Serial No. 148,475.

This invention relates to a can punching and sealing device and has for its primary object the provision of new, novel and effective means of this character for punching 5 a plurality of holes in the head of a can which may be used for pouring the contents from the can and for venting the can to permit the air to take the place of the displaced fluid and for sealing the openings 10 thus formed when the can is not in use.

A further object of the invention is to provide a device of this character which will be positive of action; one that can be actuated with utmost convenience and des- 15 patch and with little manual effort and one that can be manufactured at small cost.

Another object of the invention is to provide a device of this character which, from the nature of its construction can be kept 20 in a sanitary condition so as not to contaminate the contents of the can with which the device is used.

With the foregoing and other objects in view, the invention consists in the novel 25 construction, combination and arrangement of parts constituting the invention to be hereinafter specifically described and illustrated in the accompanying drawings which form a part hereof, wherein is shown the preferred embodiment of the invention, but it 30 is to be understood that changes, variations and modifications can be resorted to which come within the scope of the matter herein- after claimed.

In the drawings in which similar reference 35 numerals indicate like parts in the different figures,

Figure 1 is a view in side elevation of a milk can with parts in section showing a 40 sectional elevational view of our device applied thereto.

Figure 2 is a perspective view of the device removed from the can.

Figure 3 is a section on line 3—3 of Figure 45 1.

Figure 4 is a sectional view through a portion of a can showing the application thereto of a slightly modified form of our invention.

Figure 5 is a section on line 5—5 of Figure 50 4.

Figure 6 is a top plan view thereof.

Figure 7 is a plan view of a slightly further modified form of the invention.

Figure 8 is a view in side elevation thereof 55 and

Figure 9 is a view in side elevation of punch employed in connection with the form shown in Figures 7 and 8.

In the form shown in Figures 1 to 3 inclusive of the drawings, we employ a hollow punching element 10 having a diagonal cutting end 11 which, when pressed upon can be easily forced through the head of a can. The element 10 is tubular and same is curved 65 in a lateral direction to form a pouring spout 12.

A punching element 14 is employed in co- 70 action with the element 10 and same is likewise tubular and formed at its lower end with a diagonal cutting edge 15 and at its upper end with a wall or portion 16 in which a vent hole 17 is formed.

The two mating or co-acting elements 10 and 14 are rigidly joined together by a 75 metallic bar 18 which may be used as a hand grip when associating the device with a can; as a means to permit of its removal from the can when desired and as an anvil capable of being struck by a hammer or tool when driv- 80 ing the elements 10 and 14 through the head of the can.

In the form shown in Figures 4 to 6 inclusive of the drawings, the bar 18^a has a base flange 19 through which the elements 85 10^a and 14^a are extended, the said elements being of flat strip form, preferably integral with the bar 18^a. The lower ends of the elements 10^a and 14^a are formed with diagonal side edges merging into a sharp point 20 90 so that the elements can be easily driven into the can. The flange 19 forms a stop to limit the movement of the elements in one direction and to normally seal the opening formed thereby. The elements are further provided 95 with straight sides 21 which act against the walls of the formed openings to hold the elements tightly fitted therein.

In the form shown in Figures 7 to 9 inclusive of the drawings, we employ a base 100 section 22 and a removable top section or punch 23, the latter formed of a single strip of metal having a transverse bar 24 and spaced apart punching or hole forming ele-

ments 10^b and 14^b. These elements can be driven into the head of a can to form the respective openings and same can then be removed. The base section includes tapered hollow portions 25 and 26 adapted to be inserted in the openings formed by said elements 10^b and 14^b. These portions 25 and 26 are joined together by a rigid bar 27 having stop lugs 28 adapted to rest against the head of the can as shown in Figure 8. In this form of our invention, the portion 25 may be used as a pouring spout and the portion 26 as a vent when discharging the contents from the can. Normally the elements 10^b and 14^b may be used as plugs for sealing the bores of said portions 25 and 26 respectively.

Each of the bars 18, 18^a and 24 is formed

with perforations 29 whereby the device may be supported from a wall hook or the like 20 when not in use.

We claim:

A device of the type described, comprising a pair of elements for making an outlet and an inlet opening in a can, means for connecting said elements together, an outlet and an inlet pipe connected together and being insertable in the openings when said elements are removed, said elements being receivable in said outlet and said inlet pipes 30 for closing the passageways and for aiding in cleaning the passageways of foreign matter.

CHARLES W. BASSETT.
EDNA M. BASSETT.
